Filed July 24, 1962, Ser. No. 71,036

Term of patent 14 years

(Cl. D61—1)

FIG. 1

FIG. 2

FIG. 1 is a front perspective view of a rotary microfilm camera embodying our new design the right inner wall of the document exiting portal being similar in appearance to the disclosed left inner wall of such portal; and

FIG. 2 is a rear perspective view thereof.

The essential features of the design reside in the portions shown in solid lines.

We claim:

The ornamental design for a rotary microfilm camera, substantially as shown and described.
